CLAIM

I claim the ornamental design for a mount for an excavation control unit, as shown and described.

DESCRIPTION

FIG. 1 is a perspective view showing top, rear and right side side features of my new design;

FIG. 2 is a top plan view thereof;

FIG. 3 is a bottom plan view thereof;

FIG. 4 is a front elevation view thereof;

FIG. 5 is a rear elevation view thereof; and,

FIG. 6 is a right side view thereof, it being understood that a left side view would provide is a left to right reversed image of FIG. 5.

To the extent that broken lines are present in the drawings, they represent unclaimed subject matter and form no part of the present invention.

The mount for an excavation control unit is shown with a symbolic break in its length. The appearance of any portion of the article beyond the break lines forms no part of the claimed design.
